UNITED STATES PATENT OFFICE.

LAUREN CARPENTER, OF ST. JOSEPH, MICHIGAN.

MACHINERY FOR FORMING AND FASTENING BOXES AND DISHES.

SPECIFICATION forming part of Letters Patent No. 253,839, dated February 21, 1882.

Application filed November 1, 1881. (No model.)

To all whom it may concern:

Be it known that I, LAUREN CARPENTER, residing at St. Joseph, in the county of Berrien and State of Michigan, and a citizen of the United States, have invented new and useful Improvements in Machinery for Forming and Fastening Boxes and Dishes, of which the following is a full description, reference being had to the accompanying drawings, in which—

Figure 1 is a rear elevation; Fig. 2, a front view of the upper part of the machine; Fig. 3, an end view, with the lower part of the base-frame broken off; Figs. 4 and 5, rear and end views of the wire-feeding devices detached; Fig. 6, plan view of the staple forming and driving devices, one side broken off; Fig. 7, a vertical section, showing the edges of the staple forming and driving devices; Figs. 8 and 9, details of the ends of the staple forming and driving hammers or plates; Fig. 10, a cross-section of the staple forming and driving plates or hammers; Fig. 11, a modification, showing the disks or wheels for operating the staple devices by power or continuously in one direction; Fig. 12, the staple; Fig. 13, an end view of the former; Fig. 14, a cross-section of the clinch-block on line 3 of Fig. 13.

The object of this invention is to produce an improved machine for forming and fastening dish-shaped articles or boxes made of veneer or other thin material, said machine to be operated either by power or hand.

The nature of my invention consists in the devices and combinations of devices and parts hereinafter described and claimed as new.

In the drawings, A A' indicate the base-frame, A representing the uprights, and A' the braces; B, uprights or posts attached to the frame A; C, cross-timbers supporting the fastening devices; D D', cross-timbers; E, wire-spools; F, hand-wheel; F', stop pin or arm; G, dish-former; H I, cross bars or timbers supporting the springs; J K, treadles; L L', stop-block for the hand-wheel; M, spring; N N', wheels or disks for operating the staple for the forming and driving devices; a, secondary frame supporting the wire-feeding devices; b, cross-bar by which the frame a is attached to the main frame; c d, feed-wheels; c', weighted cords or wires; e, arms for operating the feed-wheels; e', ratchet-wheel; f, connecting-rods

for operating the arms e; g, the front projection on the treadle-bar h; h, the treadle-bar; i, the rods or bars supporting the former G; i', cross bar or block; j, spring; k, pivot-bar for holding up or supporting the former while the staples are being driven; l, rod connecting the pivot-bar k to the treadle K; m, the spring; n o, rods or pitman for operating the devices for forming and driving the staples; n' o', coupling-ears; p, casing or support for the staple forming and driving devices; q r, slide or hammer for cutting and forming the wire into staples; s, the staple-former; s', notches in the former for turning the ends of the wire to form the staple; t t', depression and corresponding projection for forming the middle bend of the staple; u, plate or hammer for driving the staples; u', holes through which the wire is fed; w, clinch-plates on the ends of the former; x, guides; y, set-screws; z, rubber or other springs for adjusting the pressure of the wire-feeding devices.

As shown, the base-frame is made of uprights A and inclined or bracing side posts, A', which construction gives a strong supporting-frame; but it may be made in any other desired form and made of any suitable material, the one shown being made of wood. At the upper ends of the uprights A two similarly-formed plates or cross-timbers, C, are attached, as shown in Fig. 3, and on the front side upright bars B are attached, and they are connected together at the top with a plate or timber, D', upon which the wire-spools E are mounted.

In front of the head C the wire-feeding devices are attached by a V-shaped frame, a. This frame is provided with four feed-rollers, two upper and two lower ones. The upper ones, c, are provided on their fronts with pawls or dogs, as shown in Fig. 1. The shaft upon which they are mounted is provided with a ratchet-wheel, e', the teeth of which are spaced, so that the movement given to the feed-wheel by each ratchet-tooth feeds the proper length of wire to form a staple. The ratchet-wheel is loose upon the shaft, and is provided with a collar, to which the arm e is attached, and the ratchet is operated and the feed-wheels moved by the arms e, which are attached by means of the rods f and projection g of the rod or shaft

h, as shown in Fig. 1, and they are operated by the treadle *J* and the spring *j*. The spring is of sufficient strength to raise the rod and treadle, which movement elevates the inner end of the arms *e* and turns the ratchet-wheels *c* the distance of one notch, so as to make a new engagement with the clicks or pawls upon the faces of the wheels *c*. When the treadle is depressed the inner ends of the arms *e* are forced down, turning the wheels *c*, and by their frictional contact the wheels *d*, and causing the wire to advance. The wires cross each other, as shown, so as to give the feed the proper direction by this movement.

15 In order to adjust the pressure for producing the feeding of the wire, I place weights over the wheels *c*; or the weight may be placed upon the collar of ratchet-wheel *c'*, or upon the shaft, by cords or wires *c'*, as shown in Fig. 4, a sufficient weight being attached to insure the feeding; or the friction between the wheels *c* *d* may be adjusted by the set-screws *y* and rubber or other springs, *z*, as shown in Fig. 1; but I prefer the weight to the adjusting-spring, as unskillful laborers are liable to adjust them over-tight when using set-screws.

The staple forming and driving devices are located between the plates or bars *C*, as shown at Fig. 6, and their supports or casings *p* are located at an incline, as shown in Fig. 7, so as to bring them at about right angles with the end of the former, against which the driving-hammers operate, and as the two are alike the description of the construction of one will answer for both.

35 The casing *p* is provided at its bottom interiorly with a groove which the driving-hammer fits and fills. Over this driving-hammer is placed the forming-hammer *q* and former *s*, the different widths being shown at Fig. 10. The former *s* is permanently attached to the casing, and is provided with notches *s'*, in which the staple ends are formed, and they are undercut, so that the ends of the staples 40 will stand slightly inclined toward each other. It is also provided with the depression *t*, for bending the middle of the staple downward, as shown. The forming hammer or slide *q* has at its middle a projection, *t'*, fitting into 45 the depression *t*, and its sides at the forward end are provided with projections *r*, which pass down into the notches or openings *s'*. These projections are grooved, as shown at Fig. 8, so as to take up the free end of the wire 50 and center it, and on the side where the feed occurs the projection *r* also acts as a cutter, or a part of the cutter, as the casing *p*, where the wire enters the interior, is provided with a steel die or plate, by which the wire passes, 55 and by or against which it is cut off.

60 In operation, as the forming-hammer descends it picks up the free end of the wire, carries it down to a line with the former, at which point the wire is severed and its two ends carried down into the openings *s'* over the sharp angles of the former in forming them,

and as they are free to pass into the under-cut they are bent a little past the right angle, at the same time the middle is bent down at *t*, and by bending the middle, as shown, when the hammer is retracted this bend springs back slightly, so as to loosen the staple at the ends, and also along its length, which action leaves it free to fall away from the former. While this operation is taking place the driving-hammer has been under the staple-former, as shown in Fig. 7. When the staple is formed by the action of the wheels or disks *N*, the rods *n o* retract the forming-hammers, when the staple falls just in front of the driving-hammer to the bottom of the casing *p*, with its turned ends forward, and slides down against the box or dish blank, which has been brought by the dish or box former up into a position to receive the staples, where they remain until the 85 driving-hammer descends and drives them through the blank, and fastens them firmly against the box or dish former. By this arrangement for forming and driving the staples I avoid the use of all or any devices for holding the staple between its formation and its driving, which greatly simplifies the construction and operation of the machine.

The staple devices are operated by a hand-wheel, *F*, which is attached to the same shaft 95 as the wheels *N N'*. The hand-wheel is given a reciprocating movement, the movement in one direction forming the staples, and the opposite direction driving them.

The frame *C* is provided with a stop, *L*, having an elastic cushion, *L'*, against which the limit-pin *F'* comes. The stop acts in the direction of retracting the driving devices, the dish and its former forming the stop in the opposite direction, the machine being free to 100 continue the movement of the driving-hammers until they are brought in contact with the dish or box on the former, and as the position of the dish or box former is liable to vary somewhat, I avoid any projection of the 105 driving-hammers by means of the spring *M*, the outwardly-turned point of which comes in contact with one of the arms or spokes of the hand-wheel and throws it back slightly, so as to insure the clearing of the driving-hammers 110 from the space to be occupied by the dish or box former. When the machine is to be moved continuously in one direction, either by power or hand, the stop *L* and the spring *M* are to be omitted, and the hand-wheel, which then becomes either a hand-wheel or a balance-wheel 115 and pulley, may be reduced in diameter, so as to require less movement of the hand, as in that event it would require a full turn, which makes a long movement for the hand, unless 120 the size is reduced.

In feeding in the blanks, which have been previously properly slit and scored, so as to have three parts at each end, the operator bends down the middle end pieces and slides 125 the blank over the former until it strikes the guides *x*. The foot is then removed from the

treadle J, and the spring j elevates the former with the blank. The sides of the dish-blank, as it nears the top of the cut-out portion of the cross-timbers C, come in contact with the 5 springs or side arms, a', and the side ends or corners come in contact with the inclined folding and forming springs or wires b', which brings the blank down so as to closely fold and fit over the former G, and into a position 10 where the side parts of the ends overlap the middle part, previously bent down by the operator. It is not essential that the operator bend down the middle portions of the ends, as ordinarily they will come into place without this, and additional springs or wires operating slightly in advance of the others may be used for that purpose. When in this position the ends are ready for fastening. The forming-springs a' b' are located between the 15 timbers C C, and are shown for one side at Fig. 7.

In order to prevent the blows of the driving-hammers from driving the dish-former down, the treadle K is operated, which brings the 20 bar k under the cross-head i', or a projection therefrom, which movement gives the dish-former a firm position for the driving and clinching of the staples; but if it is not desired to use two treadles a weight and cord, as indicated 25 by the dotted lines in Fig. 1, may be used in place of the bar k and its attachment with the treadle K, the object and purpose of either device being to prevent the dish-former from settling on the spring when the blows are given. The rods i are firmly attached to the 30 rod h by the cross-head i', which cross-head may be adjustably attached by means of screw-nuts on the shaft h or otherwise.

It will be seen that when the dish-former G 35 is elevated the rods f also carry up the arms e, so as to engage the ratchet and put the wheels c in position for feeding in the wire, and as the dish-former comes down the wire is fed in, and the movements are so timed by means of the 40 hand-wheels and treadles that they follow each other in proper succession without confusion, thus producing rapidly butter or other dishes or boxes made from thin veneer or other suitable material.

The staples are clinched by being driven 45 against solid plates of metal firmly attached to the ends of the dish-former, as shown in Fig. 13. These plates are slightly longer than the staples, and are grooved out, as shown at Fig. 50 14. This groove is about one-eighth of an inch in depth at its lowest part, and by this grooving the staple is nearly driven before its ends come in contact with the clinching-plate, which prevents the staples from kinking on the outside, and as the driving-hammers have sufficient force to cause the dish to follow down 55 into the grooving of the clinching-plates there is no kinking of the staples on the inside and proper clinchings are uniformly made, and as 60 in forming the staples the ends are inclined

inward, this incline causes them to project toward each other in clinching, so that a simple groove to keep them in line is all that is required for clinching them, whereby, as shown, the clinch-plates are provided with a single 70 groove; but the depression, if desired, may be provided with two or more grooves, so as to have two or more lines for the ends of the staples to move in.

For operating the machine continuously in 75 one direction, the plates or disks N N' are replaced by the eccentrics, as shown in Fig. 11, which are provided with encircling bands for operating the rods n o. These eccentrics and their bands may be arranged so as to be operated by two or by four eccentric wheels, or a double crank may be given to the shaft, to take the place of either the disks or the eccentrics, and suitable connections will be added for making the moving parts operate in their respective periods of time. By this arrangement I produce a simple and effective machine for the purpose desired; and its construction and operation are such that it is not easily damaged, or so complicated in its movements but 90 that it may be operated by unskilled laborers.

In order to prevent the staples from getting under the driving-hammer its lower or inner end is provided with a slight groove, as shown at Fig. 9, and as the middle bend of the staples holds them against the dish at that point, the middle portion of the hammer may recede, so that the sides thereof only act in driving. 95

In feeding the wire, and when the feed-wheels are, as shown, at an angle with the 100 passage into the staple-former, it will be advisable to provide guide-tubes for the turn, as shown at v', Fig. 1.

It is evident that the dish-former may be made entirely of metal, and when so made 105 guide-grooves may be made therein for the staple ends, or they may be cast with cavities, so that separate plates may be used, as when the former is made of wood.

What I claim as new, and desire to secure 110 by Letters Patent, is—

1. In a machine for forming and fastening boxes, dishes, &c., the combination of the feed-wheels c d with the ratchet e', arms e, rods f, and rod or shaft, substantially as specified. 115

2. The combination, with the dish-former, of the supporting-rods i, and suitable mechanism, such as described, for holding the said former in its elevated position, substantially as 120 set forth.

3. The staple-former s, having the notches or openings s' and the depression t, in combination with the hammer or plate q, having the projections r and t', substantially as and for 125 the purpose set forth.

4. The driving hammer or plate u, in combination with the forming-hammer q and staple-former s, substantially as specified.

5. The combination of the staple-former s 130

and hammers or plates q u with the rods n o and disks or eccentrics N N' , substantially as described.

6. The combination of the rods h i and dish-former G with the spring j and treadle J , substantially as set forth.

7. The combination of the feed-wheels c d with the staple-former s and hammer or plate g , all constructed and operating substantially as specified.

8. The combination of the feed-wheels c d , having an intermittent movement, with the staple-former s and cutting-hammer g , substantially as described.

15 9. The combination and arrangement of the

feeding devices e d , staple-former s , hammers q u , and casings or boxes p , with the dish-former G , having the grooved clinch-plates w , all constructed and operating substantially as specified.

10. The folding and forming springs a' a' and b' b'' , in combination with the dish-former G , so arranged as to fold the blank on the former as it is pressed upward to receive the staples, substantially as described.

LAUREN CARPENTER.
